(57) **CLAIM**

The ornamental design for a display screen or portion thereof with graphical user interface, as shown and described.

DESCRIPTION

The file of this patent contains at least one drawing executed in color. Copies of this patent with color drawing(s) will be provided by the Office upon request and payment of the necessary fee.

FIG. 1 is a front view of an embodiment of a display screen or portion thereof with graphical user interface;

FIG. 2 is a front view of an embodiment of a display screen or portion thereof with graphical user interface;

FIG. 3 is a front view of an embodiment of a display screen or portion thereof with graphical user interface;

FIG. 4 is a front view of an embodiment of a display screen or portion thereof with graphical user interface;

FIG. 5 is a front view of an embodiment of a display screen or portion thereof with graphical user interface;

FIG. 6 is a front view of an embodiment of a display screen or portion thereof with graphical user interface;

FIG. 7 is a front view of an embodiment of a display screen or portion thereof with graphical user interface;

FIG. 8 is a front view of an embodiment of a display screen or portion thereof with graphical user interface; and,

FIG. 9 is a front view of an embodiment of a display screen or portion thereof with graphical user interface.

The broken lines showing the display screen or portion thereof form no part of the claimed design.
